UNITED STATES PATENT OFFICE

EDWIN F. GUTH, OF WEBSTER GROVES, MISSOURI

DESIGN FOR A REFLECTOR FOR LIGHTING FIXTURES

Application filed March 23, 1932. Serial No. 43,278. Term of patent 3½ years.

To all whom it may concern:

Be it known that I, EDWIN F. GUTH, a citizen of the United States, residing at Webster Groves, in the county of St. Louis and State of Missouri, have invented a new, original, and ornamental Design for a Reflector for Lighting Fixtures, of which the following is a specification, reference being had to the accompanying drawing, forming part thereof, in which—

Fig. 1 is a front elevation showing my new design;

Fig. 2 is a perspective view; and

Fig. 3 is an end view of the reflector shown in Fig. 1.

I claim:

The ornamental design for a reflector for lighting fixtures, as shown.

EDWIN F. GUTH.
